DESIGN FOR A COOKING STOVE

Harry H. Fleer, Quincy, and Swiney Morgan,
O'Fallon, Ill., assignors to Eureka Steel Range
Co., St. Clair County, Ill., a corporation of
Illinois

Application March 26, 1934, Serial No. 51,198

Term of patent 3½ years

To all whom it may concern:

Be it known, that we, HARRY H. FLEER and SWINEY MORGAN, citizens of the United States and residents, respectively, of the city of Quincy, county of Adams, and State of Illinois, and of the city of O'Fallon, county of St. Clair, and State of Illinois, have invented a new, original, and ornamental Design for a Cooking Stove, of which the following is a specification, reference being had to the accompanying drawing, forming part thereof.

In the drawing, Fig. 1 is a perspective view of

a cooking stove embodying our new design; Fig. 2 is a fragmentary plan view of the upper frontal portion of the cooking stove, as taken along line 2—2 of Fig. 1, and Fig. 3 is a fragmentary plan view of the lower frontal portion of the stove, as taken along line 3—3 of Fig. 1.

We claim:

The ornamental design for a cooking stove, substantially as shown and described.

HARRY H. FLEER.
SWINEY MORGAN.
